UNITED STATES PATENT OFFICE.

CHARLES GRIFFIN WEBBER, OF FLUSHING, NEW YORK, ASSIGNOR TO
SARAH A. WEBBER, OF SAME PLACE.

LAMP-BURNER.

SPECIFICATION forming part of Letters Patent No. 294,417, dated March 4, 1884.

Application filed August 10, 1883. (No model.)

To all whom it may concern:

Be it known that I, CHARLES G. WEBBER, a citizen of the United States, residing at Flushing, in the county of Queens and State of New York, have invented a new and useful Lamp, of which the following is a specification, reference being had to the accompanying drawings.

My invention relates to lamp-burners, the object being to provide burners with means for readily extinguishing the light without danger of explosion and without requiring the removal of the lamp-chimney or the turning down of the wick.

The invention consists in combining with the wick-tube of the lamp a blow-tube whose upper end is provided with a valve for preventing the accidental extinguishing of the light, and whose lower end is connected to a mouth-piece.

20 The invention further consists in the combination, with the blow-tube and its mouth-piece, of a blow-pipe, whereby the light may be readily extinguished when the lamp rests upon a bracket or other support too high to admit of the use of the mouth-piece of the blow-tube.

The invention further consists in the details of construction and combinations of parts hereinafter fully described, and pointed out in the claims.

30 In the drawings, Figure 1 is a perspective view of a lamp-burner with its top cap raised to show the application of my improvement. Fig. 2 is a vertical section of Fig. 1, and Fig. 3 shows my improved blow-pipe adapted for use 35 when the lamp rests in an elevated position.

A represents a lamp-burner, which may be of any preferred general construction. B indicates its hinged top cap, C its chimney-guards, and D the wick-tube.

40 F represents a blow-tube, preferably arranged parallel with the wick-tube and extending through the perforated diaphragm a of the burner. The under side, f, of the tube F extends above its side f', and the ends f² f² are 45 preferably inclined to form a seat for a valve, G. The ends of the latter are bent and perforated to receive the ends of a pivotal rod or wire, g, supported on the outer side of the tube F by soldering or otherwise. The inner side, 50 f', of the tube F is preferably flush with the

upper edge of the wick-tube, for a purpose which will be explained.

To the lower end of the blow-tube F is secured a mouth-piece, H, whose outer end is enlarged or flaring. This mouth-piece is inclined relative to the tube F, and its outer end projects below the adjacent edge of the diaphragm of the burner.

From the construction thus described it will be apparent that upon blowing into the mouth-piece the valve G will be raised and the air discharged in an upward direction against the flame of the wick by reason of the relative arrangement of the wick and blow tubes, thus effectually preventing any downward draft within the wick-tube and consequent explosion. The valve G drops by its own weight and rests normally upon the blow-tube, to prevent the ingress of air to the flame, except when lifted by the blowing already described.

In Fig. 3 I have illustrated a flexible blow-pipe of rubber, and provided at one end with a metallic tube, I, and handle J, and at its opposite end with a mouth-piece, K. This device is adapted for use where the lamp to be extinguished rests too high up to admit of the blowing directly into the mouth-piece H. In this instance the tube I is inserted into the mouth-piece H by means of the handle J, thus leaving the mouth-piece K of the tube within easy reach.

60 An important advantage of my invention is found in the fact that by its use only an occasional trimming of the wick is necessary, since to extinguish the flame no turning down or adjustment of the wick is necessary. Where the wick is turned down each time the light is blown out, its frequent trimming is necessitated.

65 My improvement in no wise affects the regularity of the light, and affords a ready, convenient, and safe means for extinguishing the same.

It will be apparent that many slight alterations might be resorted to in the details of construction of my device without departing from the spirit of my invention; hence I do not limit 90 myself to the exact construction shown and described, but reserve to myself the right to make all such modifications as may properly fall within the scope of my invention.

Having fully described my invention, what I 95

claim as new, and desire to secure by Letters Patent, is—

1. The combination, with the wick-tube of a lamp-burner, of a blow-tube provided with a valve and mouth-piece, substantially as set forth.

2. The combination, with the wick-tube of a lamp-burner, of a blow-tube provided with a valve and flaring mouth-piece, and a blow-pipe 10 adapted to be inserted into said mouth-piece, substantially as set forth.

3. The combination, with the wick-tube of a lamp-burner, of a blow-tube whose upper end is inclined to form a valve-seat, a valve pivotally supported upon the upper end of said blow-tube, and a mouth-piece secured to the lower end of the blow-tube, substantially as 15 set forth.

4. The combination, with the wick-tube of a lamp-burner, of a blow-tube whose upper edge 20 is flush with the upper edge of the wick-tube, and an inclined mouth-piece adapted to guide the draft in an upward direction, substantially as set forth.

5. The combination, with a wick-tube and a 25 blow-tube provided with a pivoted valve and a mouth-piece, of a blow-pipe adapted to be inserted into said mouth-piece and provided with a handle, substantially as set forth.

In testimony that I claim the foregoing as 30 my own I have hereto affixed my signature in presence of two witnesses.

CHARLES GRIFFIN WEBBER.
